COOLING APPARATUS

Fabio Sergardi, Lansing, Mich., assignor to Reo Motor Car Company, a corporation of Michigan

Application May 29, 1933, Serial No. 673,391

4 Claims. (Cl. 123—196)

This invention relates to apparatus for cooling fluids and more particularly to an apparatus for cooling oil or other lubricants employed in the operation of internal combustion engines.

Heretofore, where lubricant cooling devices have been employed in connection with internal combustion engines they have usually been installed separately from the engine proper requiring extra space and also necessitating the use of a considerable quantity of tubing or other conduits, resulting in a cumbersome and costly installation.

It is therefore one object of the present invention to provide a lubricant cooling apparatus for use with internal combustion engines which may either be built into or secured to the cylinder block of the engine in compact relation thereto.

Another object of the invention is the provision of an improved fluid cooling apparatus or system.

Other objects and advantages of the invention will become apparent from a reading of the following description taken in connection with the accompanying drawings in which:

Fig. 1 is a side elevational view, partially in section, of an internal combustion engine, showing the cooling device of the present invention as applied thereto;

Fig. 2 is a broken, horizontal sectional view of parts of an engine and the present cooling apparatus, the view being taken substantially on the line 2—2 of Fig. 1;

Fig. 3 is a sectional view taken on the line 3—3 of Fig. 2, and;

Fig. 4 is a sectional diagrammatical view of the cooling tubes and associated structure taken substantially on the line 4—4 of Fig. 3.

The invention as applied to internal combustion engines of present day construction and arrangement comprises a plurality of pairs of slightly spaced telescoping tubes positioned within a casing. This casing may be positioned at least partially within the cylinder block in close proximity to the cylinders and directly in the path of cooling fluid flowing from a force pump, or other source, to the passageways surrounding the cylinders, or may be secured to an outer wall of the cylinder block. Oil or other lubricant flowing from a sump or pump is introduced into the spaces provided between the two tubes of each pair, and the cooling fluid is made to pass through the inner tubes and also around the outer tubes so that the thin film of lubricant in each pair of tubes is quickly and thoroughly cooled from all sides thereof. Provision is also

made to allow the cooling fluid to flow from the casing, around the cylinders and to continue its circuit, and also for the lubricant to be returned to the conduits comprising the main lubricating system.

Referring now to the drawings, reference numeral 10 indicates the cylinder block of an internal combustion engine to which is secured a casing, indicated generally at 11, which contains the cooling apparatus comprising the present invention. An oil filter 14 of well known construction having a connecting conduit 13 to an oil pump 12 is secured in any suitable manner to the crank case 15 and is connected by a supply conduit 16 to the cooling apparatus. A return conduit 17 from the cooling apparatus is connected to a duct 18 formed in the crank case and which carries the lubricant to the general lubricating system.

As shown in Figs. 1 and 2 the forward end of the cylinder block is extended to provide a chamber 19 within which is mounted a force pump 21 of any suitable design for forcing cooling fluid into the cylinder block and around the cylinders. The cooling fluid may be supplied to the pump 21 through a conduit 22 which may be connected to the radiator or other cooling apparatus of the engine, as is well known in the art. A passageway 23 is provided in the cylinder block between the pump chamber 19 and the interior thereof so that the cooling fluid may flow into the cylinder block and through the spaces or passageways 24 surrounding the cylinders 20.

In accordance with the present invention, when the cylinder block is formed, a portion of one side wall thereof is omitted providing an opening extending substantially the full length thereof. The back plate 25 of casing 11 is provided with flanges and may preferably be formed to fit within this opening and to extend into the interior of the cylinder block to lie in close proximity to the outer walls of the cylinders, as is clearly shown in Fig. 2. The front plate 26 of casing 11 is formed to extend slightly outwardly of the cylinder block and is also provided with flanges which coat with the flanges on the back plate to form a suitable enclosure. A sufficient number of gaskets 27 are provided between the flanged portions of the two plates and the assembly is bolted as at 28 or otherwise suitably secured to the cylinder block with additional gaskets being positioned adjacent the cylinder block. An end wall of this back plate is formed with an opening 30 which registers with the passageway 23 so that the chamber so formed is in open communication with the pump chamber 19 to re-

5 10 15 20 25 30 35 40 45 50 55

ceive cooling fluid flowing to the passageways surrounding the cylinders.

From the foregoing construction it will be seen that a casing is formed which is partially built into the cylinder block and forms an integral part thereof making a very compact and neat arrangement whereby space is conserved and connecting tubing is practically eliminated.

The casing is provided with suitable openings 29 at points between each pair of cylinders and extended nozzle members 31 are secured to the casing in registration with some of the openings 29 to carry the cooling fluid well into the spaces between the cylinders.

15 It will thus be seen that cooling fluid flowing from the pump mechanism 21 passes through the passageway 23 into the chamber 11 and then out through the openings 29 and nozzles 31 into the spaces surrounding and between the cylinders.

20 From the cylinder passageways the cooling fluid may continue its circuit back to the cooling radiator as is well understood.

To cool the oil or other lubricant employed to lubricate the moving parts of the engine, a cluster of tubes 32 is suitably secured within the casing 11 in contact with the cooling fluid therein and extends longitudinally thereof but is slightly spaced from the ends. Lubricant is passed through this cluster of tubes to be cooled and is 30 then returned to the lubricating system.

The constructional features of the tubing cluster reside in the provision of a plurality of hollow tubes 34, herein referred to as the "outer tubes", which connect a pair of spaced, hollow 35 headers 33 and are in open communication with the interiors thereof as shown in Fig. 4. Hollow tubes 35, herein referred to as the "inner tubes", somewhat smaller in diameter than the tubes 34 are telescopically positioned within the tubes 34, 40 the walls thereof being equally spaced from the walls of the tubes 34 to form small passageways A between each pair of tubes. These tubes 35 extend to the exteriors of the hollow headers 33 to be in open communication with the interior of the 45 chamber 11 so that cooling fluid may pass therethrough. As shown in Figs. 2 and 3 the pairs of tubes are spaced from each other providing spaces B therebetween through which the cooling fluid may circulate within the casing 11.

50 A suitable casting 36 is positioned interiorly of the chamber 11 on the front plate 26 approximately midway between the ends thereof and is provided with parallel ducts 37 and 38 to which are connected the oil intake conduit 16 and the 55 return conduit 17 respectively which in turn are secured to a similar suitable casting 36' positioned correspondingly on the exterior of the front plate. The two castings 36 and 36' are secured together and to the front plate with gaskets by bolts or 60 other suitable means.

In the operation of the present device, the cooling fluid enters the cooling chamber 11 from the force pump 21 and travels through the inner tubes 35 as shown by arrows in Fig. 4, as well as 65 around the outer tubes 34 through spaces B therebetween and then through the openings 29 and 31 into the passages between the cylinders. The lubricant flowing from the oil pump 12 passes 70 through the filter 14 and the intake conduit 16, passageways 37 and 40, and tube 39 into the interior of the forward hollow header and then into the spaces A between tubes 34 and 35 to the interior of the opposite header and back through conduit 43, and passageways 41 and 38, to the 75 return line 17, also shown by arrows in Fig. 4.

The view of Fig. 4 is slightly exaggerated to better show the construction, but in actual practice the spaces A between the interior walls of the tubes 34 and the exterior walls of the tubes 35 are very small so that lubricant passing between the two tubes is spread into a thin film and quickly cooled inasmuch as the cooling fluid surrounds it on all sides. This space, of course, may be varied to suit existing conditions.

It will be seen that by the present invention 10 a very compact and efficient cooling apparatus has been provided for cooling the lubricant of an internal combustion engine. The cooling apparatus, as shown, is built into the cylinder block making for a very compact arrangement, thus 15 conserving space and substantially eliminating costly tubing and conduits, but could be conveniently secured to the exterior of the cylinder block if desired.

While the cooling apparatus per se has been 20 designed for and is shown in connection with an internal combustion engine, it will be apparent that it would be readily adaptable to other cooling purposes and that the construction as shown in the drawings may take other forms without departing from the spirit or scope of the invention 25 which is to be limited only by the appended claims.

What is claimed and desired to be secured by Letters Patent is:

1. In combination with an internal combustion engine having a cylinder block, a pressure lubricating system for supplying lubricant to the engine bearings and a pump for supplying cooling fluid under pressure to said cylinder block, 35 a casing positioned partially in said cylinder block in communication with said pump and the interior of said cylinder block, a pair of spaced hollow headers in said casing, a cluster of tubes extending between said headers and consisting of 40 pairs of tubes arranged one within the other, each tube of each pair being spaced from the other to provide one passage between the walls thereof and another passageway within the inner tube, the outer tube of each pair terminating within each of the hollow headers in open communication with the interiors thereof, and the inner tube of each pair extending through each of the headers to the exteriors thereof, means carrying the cooling fluid to said inner tubes, 50 means carrying the lubricant to one of said headers and thence to said passageway between the tubes, conduit means between the interior of said casing and said cylinder block, and means connected to the interior of the other header for 55 conveying the cooled lubricant to the engine bearings.

2. In combination with an internal combustion engine having a cylinder block, a pressure lubricating system for supplying lubricant to the engine bearings and a pump for supplying cooling fluid under pressure to said cylinder block, a casing positioned partially in said cylinder block in communication with said pump and the interior of said cylinder block, a pair of spaced hollow headers arranged in said casing, a tube connecting the interiors of said hollow headers, a second tube within said first tube and spaced from the walls thereof providing a passageway between the two tubes, said second tube extending 70 to the exteriors of said headers, means conveying the lubricant to the interior of one header and thence to the passageway between the two tubes, and means conveying the cooling fluid to said second tube and also to the interior of said casing 75

whereby said cooling fluid surrounds said first tube and also is carried through the second tube.

3. In combination with an internal combustion engine having a cylinder block, a pressure lubricating system for supplying lubricant to the engine bearings and a pump for supplying cooling fluid under pressure to said cylinder block, a casing partially positioned in said cylinder block, connections between said cooling fluid pump and the interior of said casing and between the interior of said casing and said cylinder block, a pair of spaced telescoping tubes within said casing, means for conveying the lubricant to the space between said tubes, and means conveying the cooling fluid to the inner tube and also to the interior of said casing whereby said cooling fluid

flows past all tube surfaces with which the lubricant is in contact.

4. In combination with an internal combustion engine having a cylinder block, a pressure lubricating system for supplying lubricant to the engine bearings and a pump for supplying cooling fluid under pressure to said cylinder block, a casing partially positioned in said cylinder block, connections between said cooling fluid pump and the interior of said casing and between the interior of said casing and said cylinder block, a pair of spaced telescoping tubes within said casing, means conveying the lubricant to the space between said tubes, and means conveying the cooling fluid to the inner tube.
